Primary Examiner — Elizabeth Albert

(74) Attorney, Agent, or Firm — Quickpatents, LLC;
Kevin Prince(57) **CLAIM**

I claim the ornamental design for a drawing template, as shown and described.

DESCRIPTION

FIG. 1 is a perspective view of a drawing template showing my new design;

FIG. 2 is a front elevational view of FIG. 1, the rear elevational view being a mirror image thereof;

FIG. 3 is a left-side elevational view of FIG. 1, the right-side elevational view being a mirror image thereof; and,

FIG. 4 is a top plan view of FIG. 1, the bottom plan view being a mirror image thereof.

1 Claim, 2 Drawing Sheets**FIG. 1**

FIG. 2

FIG. 3

FIG. 4
